UNITED STATES PATENT OFFICE.

OSCAR D. GUTH, OF ST. LOUIS, MISSOURI, ASSIGNOR TO THE EDWIN F. GUTH COMPANY, OF ST. LOUIS, MISSOURI, A CORPORATION OF MISSOURI.

SUPPORTING MEANS FOR LIGHTING FIXTURES.

Application filed July 15, 1925. Serial No. 43,736.

My invention relates to the art of illumination, and particularly to means for supporting lighting fixtures, and has for its object to provide adjustable means which 5 will also be adaptable for various assemblage of parts for the purpose of providing such an assembly as will be adapted to meet practically any condition which exists with relation to the outlet box or the length of 10 the canopy of the fixture to be installed.

A further object is to provide such a lighting support as will be adapted for seating and securing on very shallow or exposed outlet boxes.

15 It is a well recognized fact in the lighting fixture art that while junction and outlet boxes are more or less standard, there are types which are known as deep boxes and types that are known as shallow boxes, and 20 others known as cable boxes which are exposed beyond the finished plaster. It is to meet the conditions brought about by these varying depths of outlet boxes that my device has been produced, and this constitutes 25 one of the principal objects of my invention.

In connection with the above, it is my purpose to provide such a support that it can be utilized for the purpose of receiving and securing canopies of various lengths.

30 A further object is to provide means whereby in the assemblage of the parts, the socket will be anchored against turning, so that in pull sockets the chain may be positioned as desired and it will remain fixed in 35 that position.

My invention consists of certain details of construction in which

Fig. 1 is an elevation partly in vertical section to show the interior construction;

40 Figs. 2, 3 and 4 are detail views of the construction of my device;

Fig. 5 is a view of the details of construction of a modified form.

45 Referring to the accompanying drawings, the reference numeral 10 is used to indicate an outlet box provided with the usual screw-threaded stud 11. These studs are common in all outlet boxes. The numeral 12 indicates a bridge which I employ, having its 50 ends 13 and 14 offset from the main body portion, as shown, and I provide a screw-threaded orifice in the center of the bridge and on each end thereof, as shown. The numeral 15 indicates a hickey strap, U shaped in conformation, provided on one

side with a screw-threaded orifice, to engage the stud 11, and in its other side with a screw-threaded orifice to mate with the screw-threaded orifice in the main body portion of the bridge 12.

60 The numerals 16 and 17 indicate elongated set-screws to engage the screw-threaded orifices in the bridge ends 13 and 14, respectively, and the numeral 18 indicates a set-screw to pass through the central orifice of the bridge end engage the screw-threaded orifice in the hickey strap.

65 While I have referred to the central orifice in the bridge being screw-threaded to receive screw 18, my device will function equally as well by omitting the screw threads in this orifice and permitting the screw 18 to pass through this strap and engage the screw-threaded orifice in the hickey where it may be drawn to its seat, holding the strap firmly 70 in position on the junction box.

75 The bridge 15 is made with its central portion (in which the central orifice is formed) formed for what is known as a "knock-out," as is shown at 19. This means 80 that the central portion of the bridge has been punched so that a circular section is supported by a very thin metal connection with the main bridge and that this piece may be knocked out easily by a tap with a 85 hammer.

85 The socket 22 which I employ is formed with a pair of longitudinal grooves 20 and 21, in which the screws 16 and 17 are designed to pass, the positioning of these 90 screws being such that the space between them is just sufficient therefor.

95 The canopy I employ is designated by the numeral 23 and this is provided with key-hole slots 24 and 25 to receive the setscrews 16 and 17, respectively, the enlarged portion of the said slots being designed to permit the heads of the screws to pass therethrough and smaller portion of the slots being designed to receive the shafts of the set-screws 100 when the canopy is turned slightly.

105 The numeral 26 indicates a threaded collar of insulating material which is designed to engage the screw-threaded end of the socket and secure it within the canopy base, said collar having also screw threads formed on its forward portion to receive the screw-threaded collar 27.

110 The numeral 28 indicates a glass shade I employ. In practical operation, where it is

desired to mount a fixture having a canopy provided with the keyhole slots 24 and 25, the iron bridge is secured to the junction box through the medium of the hickey strap 5 being mounted to the stud on the junction box and the screw 18 passing through the orifice in the bridge and into its receiving orifice in the hickey strap and drawn firmly to its seat. The bridge ends thus overlie 10 the sides of the junction box, or rather rest upon the sides thereof. The canopy securing screws 16 and 17 are then adjusted to the desired length in the bridge and the canopy 23 inserted in them, the heads of the 15 screws 16 and 17 coming through the enlarged portions of the slots 24 and 25, respectively. The canopy is then rotated slightly until the shafts of the screws have entered the smaller portions of the keyhole 20 slots. The screws 16 and 17 are then rotated until they firmly hold the canopy to the junction box.

A socket 22 has, obviously, first been placed in position within the canopy and the 25 screws 16 and 17 have engaged their respective grooves 20 and 21, and lie therein, thus holding the socket against rotation. As stated, the end of this socket projects beyond the canopy and the threaded collar 26 30 is positioned thereon. The glass shade then is inserted over screw-threaded collar 26, and the second screw-threaded collar 27, which is placed inside the glass shade, engages the screw-threaded collar 26 and is rotated to 35 its seat, thus holding the glass in the shade firmly in position. The glass shade is formed with a lip to extend over the set-screws 16 and 17, thus effectually concealing all of the securing parts.

40 To demonstrate the different assemblage of the parts, in order to accommodate this support to canopies of various lengths, it will be noted that the bridge may be turned completely around so that the ends of the 45 bridge instead of resting against the sides of the junction box will be spaced at quite a distance therefrom. In this event, the screws 16 and 17 project upwardly at a much greater distance than they would under normal conditions, and thus a canopy of a much 50 longer collar could be accommodated. Short collar canopies can be taken care of, to a very large extent, by seating the screws 16 and 17 further in their screw-threaded orifices, and if it is desired to utilize a canopy 55 with an extremely short neck, the knock-out portion of the bridge is tapped with a hammer and the orifice in the bridge thus so enlarged that the bridge fits directly over the 60 stud in the junction box, in which event, a nut 29 is used to fasten the bridge to the junction box. The bridge also may be placed between the arms of the hickey strap, or on either side thereof, which, obviously, 65 provides for many degrees of adjustment.

As will also be noted, if it is desired to secure a housing directly to the junction box and to have a canopy fit flush in the said housing, the metal bridge will be reversed and the central securing screw passed 70 through the central orifice in the housing, and to and through its receiving orifice in the U shaped strap. This permits the central portion of the metal strap to be countersunk somewhat through the opening of the 75 housing.

This construction also provides for the outer ends of the strap being spaced outwardly from the housing to permit of adjustment of the elongated screws which receive the canopy. Thus it is seen that my device is adaptable to practically any desirable adjustment for the securing of supporting means for lighting fixtures.

Having thus described my invention what 85 I claim and desire to secure by Letters Patent of the United States is:

1. A support for lighting fixtures, comprising a U shaped metal strap to engage the stud of a junction box, with a screw-threaded orifice in the outer member thereof; a metal bridge with offset ends, there being screw-threaded orifices in each of said ends; a knock-out plug in the center of said bridge, having screw-threaded orifices therein; a set-screw to engage the screw-threaded orifice of the bridge and the screw-threaded orifice of the outer member of the metal hickey strap; elongated headed screws adapted to be seated in the screw-threaded orifices in the ends of the metal bridge; a lamp socket with longitudinal grooves to be engaged by the aforesaid elongated screws; a canopy having oppositely disposed keyhole slots to receive the heads of the elongated screws; a glass shade to be seated over the end of the light socket, the lip thereof engaging the outer end of the canopy; a screw-threaded collar to engage the screw-threaded end of the socket, and having a flange to engage the inner surface of the glass shade and hold it in position on the canopy, substantially as shown and described.

2. A lighting fixture support, comprising a U shaped hickey strap to be secured to the stud of the junction box; a metal bridge with offset ends adapted to be secured to the hickey strap, and means to secure it thereto, there being screw-threaded orifices in the ends of said metal bridge; elongated screws to be received by the screw-threaded orifices in the metal bridge; a lamp socket to fit between the two said screws, there being longitudinal grooves in said socket to receive the said screws; a canopy to fit over the aforesaid screws and socket, there being key-hole slots in the said canopy to receive the heads of the aforesaid elongated screws; a glass shade to fit over the end of the socket and engage the forward end of the canopy,

with means to secure said shade to the canopy.

3. A support for lighting fixtures, comprising a metal bridge with offset ends to be secured to the stud of the junction box and means to secure it thereto, there being screw-threaded orifices in the offset ends of said lug; elongated headed screws to be seated in said screw-threaded orifices; a lamp socket provided with longitudinal grooves to receive the aforesaid elongated

screws; a canopy provided with keyhole slots to fit over the aforesaid bridge, the heads of the elongated screws projecting through the said slots; means whereby a slight turn of the canopy will seat the elongated screws in the narrow portion of the said slots; a glass shade to engage the end of the canopy and fit over the socket, and means to hold the shade in position thereon. 15

OSCAR D. GUTH.
